CLAIM

The ornamental design for a hitch insert, as shown and described.

DESCRIPTION

FIG. 1 is a perspective view of a hitch insert according to the present invention shown attached to the hitch of a motor vehicle.

FIG. 2 is a top view of the hitch insert of FIG. 1.

FIG. 3 is a front view of the hitch insert of FIG. 1; and, FIG. 4 is an end view of the hitch insert of FIG. 1.

The broken line showing of environment is for illustrative purposes only and forms no part of the claimed design.
